UNITED STATES PATENT OFFICE.

BRUNO SCHERL, OF ERFURT, GERMANY.

CONSTRUCTION AND ARRANGEMENT OF SITTING AND BED ROOMS IN MANSIONS OF ALL KINDS, ESPECIALLY HOTELS, SANITARIUMS, AND THE LIKE.

No. 894,068.

Specification of Letters Patent.

Patented July 21, 1908.

Application filed October 31, 1907. Serial No. 400,015.

To all whom it may concern:

Be it known that I, BRUNO SCHERL, merchant, a subject of the King of Prussia, German Emperor, residing at Erfurt, Kingdom of Prussia; German Empire, have invented certain new and useful improvements in the construction and arrangement of sitting and bed rooms in mansions of all kinds, especially hotels, sanitariums, and the like, of which the following is a specification.

The present invention relates to the construction as well as the arrangement of sitting and bed-rooms in hotels, sanitariums and the like, which, while utilizing the available space to the greatest advantage, allows great convenience to the occupants, gives the advantages of a sitting and bedroom with a single room, facilitates attendance and prevents the guests meeting with the servants.

The arrangement is such that for each bedroom there are two entrances entirely separated from one another, one of which leads to a corridor which is only arranged for servants, while the other communicates with a balcony or veranda, arranged between the rows of windows outside the building which is only intended for the use of guests. By this arrangement the guests are not molested by the servants and the guests do not hinder the servants in working. As soon as a guest leaves the room passing on to the balcony or veranda an automatic signal arranged beside or above the corridor door, is operated, which indicates to the servants that the respective room is unoccupied and can be set in order. Further, in order to keep the servants away from the rooms as much as possible, the beds are arranged on rollers so that they can be moved in the longitudinal direction into the servants corridor through an aperture, in the wall so that when in the pushed-in position, that is to say in the room, the head-end closes the aperture and during the day the bed is pushed outside into the corridor, the foot-end closing the aperture in the wall. This arrangement enables the beds immediately after the rising of the guests to be pushed out of the room so that the room can be put in order in the shortest time ready for the reception of guests, while outside of the room the beds can be attended to and made, without making the room dusty.

In order to make the servant-corridor as

narrow as possible, the beds can also in the pushed-out position partly project into the room and this part in the room can be covered by means of a casing having the appearance of a table or cupboard. In a similar manner, to the beds, the dining-tables and cars for trunks and luggage are arranged movable through apertures in the wall into the servant corridor. The annexed drawing illustrates as an example forms of construction and arrangement of the invention.

Figure 1 is a front elevation of a hotel having the rooms arranged and provided with the improvements above described. Fig. 2 is a plan showing the arrangement of the rooms. Fig. 3 is a vertical section. Figs. 4 and 5 illustrate a modification of the arrangement of the beds. Fig. 6 shows the trunk-car and Figs. 7 and 8 the movable dining-table.

Between the rooms 1 and 2 a corridor 3 is arranged in a known manner, but which is not accessible to guests and servants as usual hitherto, but only to the latter. This corridor is in connection with a luggage-elevator 4 which is arranged towards the front of the building, and also with a passenger lift 5 and stairs 6, which stairs can be used by the guests in any emergency as a safe means of descent. The guests can get from their rooms to the said stairs through doors connecting each room to the corridor. In the absence of the guest this door serves for the servants to enter the room, for the purpose of setting it in order. As already stated, the absence of the guest is automatically indicated in the corridor for instance electrically by means of an appearing inscription or any other sign. This electric device is operated by the door, through which the guest leaves the room. The sign may appear on, above, or beside the corridor-door. For the same purpose also an acoustic or optical signal can be used.

Besides the corridor 3 between the rows of windows, on the outer-wall of the building or on the interior of the mansion, are arranged balconies or glass covered verandas 8 arranged for the guests, to which the lifts 9 lead or the principal-stairs, connecting the main entrance of the hotel with all the floors. From these verandas steps 10 lead to each room 1 and 2 the passage of which is closed at the lower or upper end by means of a door. In the first case the steps are not visible.

from the veranda and are closed towards the room by a decorative railing and gate. In the latter case the steps are visible from the glass-veranda as the door is at the upper end 5 of the steps and the latter therefore cannot be seen from the room.

The furniture of the rooms consists essentially of tables 11, dining-table 12, beds 13, luggage car 14 and bath and water-closet 10 arrangement 15. In the smaller rooms 2 one bed and the bath-arrangement is omitted. The beds 13 are mounted, as clearly shown in Fig. 3, on rollers and are movable in the longitudinal direction. At the two long sides of 15 the beds are arranged as low as possible longitudinal rails or grooves are arranged, on which, or in which run on each side two small rollers, which correspond with the said rails or grooves arranged in the wall-aperture 20 through which the bed passes, so that the beds when being pushed in or pulled out are guided straight and do not strike the walls. By means of this arrangement the beds can 25 be drawn in and out of the room 1 in such a manner, that the foot or the head-end 16 of the beds fully closes the wall aperture. If the space which the beds require in the corridor 3 is to be restricted as much as possible, they are in the pushed out position partly 30 inclosed in a cupboard or table-like casing 17 arranged in the room (Figs. 4 and 5). In order to enable the beds to be attended to in the corridor without troubling the guest, linen cupboards x are arranged above the 35 beds which however can also be arranged to stand opposite to the rooms in the middle of the corridor.

The luggage cars 14 serve to bring the luggage, raised by the elevator 4 into the relative room 1 or 2. In order to keep the luggage out of sight of the guest, the cars 14 are 40 moved in corresponding casings 18, which are in connection with the room by spring closing doors 19. If the guest wants the luggage, the servant pushes the luggage car 45 into the room by means of a handle 20, whereby by the doors 19 automatically open, automatically closing in drawing the luggage car 14 out again. Of course the luggage car 14 can 50 also be drawn in and pushed out by the guest himself after having opened the doors 19.

In order not to bring the servants into contact with the guest in the rooms 1 or 2 when serving food and beverages ordered, the 55 dining-tables 12 are movably arranged in the wall 21, Fig. 3, in such a manner that they can be pushed out into the corridor 3 through an aperture in wall 23 closable by means of a flap 24 where they remain until the 60 guests want to be served, which can be announced for instance by means of a signal. Only then are the tables 12 laid and with the food to be served pushed into the room.

Figs. 7 and 8 show an example of construction of the table 12 which is movably ar-

ranged in the wall. The table slides by means of rollers 25 in a U-shaped guide 26 provided in the wall 21, the table being guided in position and prevented from striking the wall by rollers 27 and iron guide 28. 70 The arrangement is such that the tables can be moved by an endless rope 29 running on pulleys which is worked from the outside by the servants, by means of crank-gearing.

Claims

1. A building of the class described having a plurality of guest chambers, a corridor separated from said chambers and adapted for the use of servants, and a veranda separate from the said corridor and communicating 80 with and depressed below the floors of the guest chambers.

2. A building of the character described comprising a plurality of guest chambers, a servant corridor divided off from said chambers, a veranda depressed below the floors of the guest chambers and having flights of stairs communicating with the guest chambers, and an elevator separated from the corridor and communicating with the veranda. 85

3. A building of the class described comprising a plurality of guest chambers and a servant corridor on each floor, a veranda extending about the exterior wall of the building and communicating with the guest chambers on the respective floors, said veranda being depressed below the windows of the guest chambers with which it communicates and an elevator separated from the servant corridors on each floor and communicating with 95 the respective verandas.

4. A building of the class described comprising rows of guest chambers arranged on opposite sides of the building, a servant's corridor extending longitudinally between the 105 rows of guest chambers, a veranda communicating with the several guest chambers and separated from the servant's corridor, and entrance and exit means for the servant's corridor separate from the veranda. 110

5. A building of the class described comprising a guest chamber, a partition forming one wall thereof and dividing said chamber from a servant's corridor, said partition being provided with an opening, a pair of horizontal guide ways extending through the opening in said partition, each having a pair of upper and lower tracks thereon, a table mounted to move horizontally through the opening in said partition so as to occupy a 115 position either within the guest chamber or a position in the servant's corridor, and a pair of rollers mounted on each longitudinal edge of said table and arranged to coöperate respectively with the upper and lower tracks of 120 said guide ways.

6. A building of the class described comprising a guest chamber, a partition forming one wall thereof and dividing said chamber from a servant's corridor, said partition being 125

provided with an opening, a pair of guide ways extending horizontally through said opening in the partition, each guide way being of substantially U-form and providing 5 upper and lower guide ways, a table mounted to operate horizontally through said opening so as to occupy a position either within the guest chamber or a position within the servant's corridor, a pair of rollers mounted in 10 each longitudinal edge of said table and arranged to coöperate respectively with the upper and lower tracks of the respective guide way, and supplemental rollers also mounted on the table and coöoperating with the guide 15 way to prevent edgewise movement of the table.

7. A building of the class described comprising a guest chamber, a partition closing one side thereof and separating said chamber 20 from a servant's corridor, said partition being provided with an opening, a casing arranged in alinement with the opening in the partition and projecting into the servant's corridor, the top wall of the casing being provided 25 with a pair of longitudinal slots, a pair of swinging doors arranged to close the opening in the partition, and a baggage car guided to operate through said opening so as to occupy

a position either within the guest chamber or a position within said casing, a handle being 30 provided on said car and having portions adapted to extend through the slots in the casing to a part above the latter whereby the car may be manipulated by a servant within the servant's corridor. 35

8. A building of the class described comprising a guest chamber, a partition forming a wall thereof and dividing said chamber from a servant's corridor, said partition being provided with an opening, a baggage car 40 guided to operate through said opening, a casing projecting from said partition into the servant's corridor and adapted to inclose the baggage car when occupying a position therein, the end of the partition being open 45 to permit loading of the car, and means attached to the car and operative from the exterior of said casing for permitting the car to be moved into and out of said guest chamber.

In testimony whereof I have hereunto set 50 my hand in presence of two subscribing witnesses.
